UNITED STATES PATENT OFFICE.

GEORGE S. THOMPSON, OF HOCKESSIN, DELAWARE.

MEANS OF COMMUNICATION BETWEEN AVIATORS.

1,310,810.

Specification of Letters Patent. Patented July 22, 1919.

Application filed October 15, 1918. Serial No. 258,193.

To all whom it may concern:

Be it known that I, GEORGE S. THOMPSON, a citizen of the United States, and a resident of Hockessin, in the county of New Castle 5 and State of Delaware, have invented certain new and useful Improvements in Means of Communication Between Aviators, of which the following is a specification.

While applicable to various other uses and 10 conditions my improvements are designed more particularly for the benefit of aviators as a means of communication, for instance, between a pilot and a machine companion during flight. It is well known that 15 ordinary conversation through the atmosphere is practically impossible while traveling at high speed owing to air pressure and velocity, and various devices have been devised to obviate this difficulty with 20 different results.

The main object of my invention is to 25 effectually exclude extraneous air from a flexible speaking tube by the use of ear muffs and a mouth piece adapted to maintain air tight contactual bearings around the ears of one aviator and the mouth of his 30 companion, so that the vibrations of air within the tube caused by the voice of the speaker will be transmitted to the listener without interference, all as hereinafter fully set forth,—the invention consisting in the 35 specific combination and arrangement of parts described and claimed.

In the accompanying drawings,

Figure 1, is a view illustrating the practical application and use of my improved means of oral communication;

Fig. 2, is a general perspective of the 40 apparatus spread apart for convenience of illustration;

Fig. 3, is a sectional detail of one of the ear shields;

Fig. 4, is a sectional detail of the speaking 45 trumpet.

B, is a body belt to which the rigid bifurcated Y coupling C, is attached. The Y coupling C, is of course tubular, and its bifurcated branches c, c, afford 50 means for connection with the lower ends of flexible tubes e, e, the other extremities of which are connected with the ear shields E, E. The other member c', of the Y coupling C, affords means for connection with 55 one end of a flexible tube m, the other end

of which tube is connected with the speaking trumpet M.

The belt B, is preferably provided with a bracket clip b, for the support of the speaking trumpet M, when the latter is not 60 required for actual use.

The body or funnel portion m', of the trumpet M, is preferably formed of rigid material, but the mouth piece m², thereof is 65 formed of elastic resilient material, preferably relatively soft rubber, so that by pressing the outer edges m³, of said mouth piece m², over the lips of the speaker and against the parts of the speaker's face immediately adjacent to his lips, an air tight contactual 70 connection may be established therewith, sufficient to exclude extraneous air even though the latter may be passing at relatively high velocity and pressure. To this end the outer edge m³, of the mouth piece 75 m², is shaped to conform approximately to the contour of the face of a speaker between the chin and nose, so that comparatively slight hand pressure applied to the trumpet M, will be sufficient to insure an air tight 80 closure of the mouth m², of the trumpet as related to the physiognomy of the speaker.

The ear pads or muffs E, E, are essentially 85 circumscribing shields for the isolation of the ears of the pilot or other person to be communicated with,—the main object being the exclusion of all extraneous air pressure, sounds, or vibrations, so that the words or signals transmitted from the trumpet M, 90 through the tubes m, c, c', e, e, to the interior of the ear shields E, E, may be heard clearly and distinctly by the wearer and listener.

To this end the ear shields E, E, are connected together by a suspender or dome 95 strap or straps e', e', and by chin straps e², e², and buckle e³, or equivalent fastening device, in such manner that said shields when properly positioned over the ears of the wearer, may be firmly secured, tightened, 100 and held against the sides of the head so as to effectually inclose and protect the ears. Ordinary packing or padding of the shields will not suffice to effect a perfectly satisfactory seal that will be impervious alike to 105 sound and air pressure, and an essential feature of my invention consists in attaining this desideratum of a perfect contactual seal between shield and wearer by means of elastic resilient contactual pads or cush- 110

ions e^4 , e^4 , made to conform to and surround the ears of the wearer,—and held taut and tight against the sides of the head by means of the chin straps e^2 , e^2 , and buckle e^3 , acting in conjunction with the suspender strap or straps e' . These elastic resilient cushions e^4 , e^4 , are preferably pneumatic in character, although rubber cushions with a fluid filling other than air might be substituted with like effect, so that I do not limit myself in this respect. In any event each circumscribing elastic resilient cushion e^4 , is attached to a base plate e^5 , formed with a nipple e^6 , for connection with one of the flexible tubes e , as will be understood by reference more particularly to Fig. 3, of the drawings, by which it will be seen also that the inner side of the base plate e^5 , is preferably provided with a perforated pad of felt e^7 , or equivalent material, for direct contact with the ear of the wearer.

Fig. 1, gives a general idea of the application and use of my improved appliance for transmitting speech from one person to another to the exclusion of all other sounds or interference mediums. Thus equipped one person can positively communicate with another in an aeroplane traveling at maximum or any other speed without difficulty or stress of voice, as the complete exclusion of extraneous air and pressure renders even a whisper audible to the listener. In attaining this perfection of result two of the essential features are the elastic resilient

mouth piece m' , of the speaking trumpet 35 and the elastic resilient cushions e^4 , of the ear shields E. Other incidental features are important in rendering effective these two essential features, as for instance the bifurcated coupling C, and its flexible tubular connections. All combine in a unitary construction and arrangement of parts to afford an appliance rendering vocal communication possible under conditions that would otherwise be prohibitory.

It is to be understood that companion aviators, as a pilot and observer, gunner, or other passenger, are to be equipped alike with duplicate means of vocal communication,—Fig. 1, showing only one set of apparatus for convenience of illustration.

What I claim as my invention and desire to secure by Letters Patent is:

Means for vocal communication substantially such as described, comprising ear 55 shields, a speaking trumpet, a body belt, a tubular coupling piece attached to said belt, flexible tubes connecting the ends of said coupling with said ear shields, means for securing said ear shields upon the head 60 of a listener, and a flexible tube connecting the other end of said coupling with said speaking trumpet.

GEORGE S. THOMPSON.
